CLAIM

I claim the ornamental design for a lid, as shown and described.

DESCRIPTION

FIG. 1 is a perspective view of a lid;

FIG. 2 is a top plan view of the lid;

FIG. 3 is a front elevation view of the lid;

FIG. 4 is a right side elevation view of the lid;

FIG. 5 is a rear elevation view of the lid;

FIG. 6 is a left side elevation view of the lid; and,

FIG. 7 is a bottom plan view of the lid.

In the drawings, the broken lines show portions of a lid that form no part of the claim.

1 Claim, 3 Drawing Sheets
